UNITED STATES PATENT OFFICE

2,005,244

VAPORIZER

Wilhelm Schmidt, Berlin, Germany

Application January 31, 1934, Serial No. 709,124

4 Claims. (Cl. 128—192)

This invention relates to a method for producing therapeutic gases, such as are employed for treating abscesses (also cancer), skin-, blood- and infectious diseases. It is known to employ natural gases, such as oxygen, for treating diseases. The novelty consists in that the therapeutic gases are produced by heating a mixture of chemicals. The mixture is composed of ammonia- and alkali salts, halogens, triacid alcohol, organic compounds of aliphatic and aromatic groups and esters, and also cyclic compounds in the presence of a highly active oxygen transmitter. By highly active oxygen transmitter is meant a chemical compound, which is capable of giving up excess oxygen, whereby the generation of poisonous or injurious gases is prevented.

These substances are, according to the invention, gasified by electrically heating the mixture of chemicals in a glass cylinder placed in a metal cylinder. The chemicals are heated to a temperature of about 200 to 230° C., thereby initiating the gasification. The gases developed are drawn off by a cock provided on the apparatus and either employed for external treatment of the diseased portions of the body or introduced into the lungs, stomach or other cavities of the body for internal treatment. The curative gases employed are harmless.

Successful results have already been obtained in the case of abscesses (also cancer) and skin diseases, a mixture of chemicals having been employed which was composed of the following components:—

	Percent
Sodium iodate	0.84
Sodium chlorate	6.
Hexamethylene tetramine	4.80
o-oxyquinoline sulphate	0.36
Hydrochloric quinine	0.36
Potassium permanganate	3.60
Ammonium chorate	48.03
Benzoic benzyl	6.
Glycerine	30.01

For treating other diseases either the medicinal mixture is changed by omitting certain substances or by adding other substances, or the proportion of the substances is changed.

An apparatus for producing the therapeutic gases is illustrated in vertical section by way of example in the only figure of the accompanying drawing.

In an outer cylindrical container *a*, preferably consisting of a drawn brass tube with a good tin-plating in the interior, a cylindrical con-

tainer *b* made of copper or brass and tin-plated on the inner and outer sides is inserted, this latter container serving for accommodating a glass cylinder *c*. The chemicals are charged into and heated in the glass cylinder *c* which is made of a special glass capable of withstanding high temperatures. An electric heating element, for example a heating coil *d*, serves for heating the mixture and is separated from the chemicals to be gasified by a copper cylinder *g* with a good tin-plating on the outer side, so that an annular gasifying space is produced between the cylinder *g* and the glass cylinder *c*. The heating element *d* is attached to and insulated from a cap *e* which hermetically closes the upper end of the cylinder *g*. The heating element *d* is connected with two plugs *f* which serve for connecting with a source of electric current, for example the lighting mains.

On the bottom of the cylinder *g* lies a copper disc *h* having a diameter corresponding to the internal diameter of the glass cylinder *c*. Thus, a uniform distribution of the heat and a determined distance between the glass cylinder *c* and the copper cylinder *g* are obtained. It is important that the cylinder *g* has on its outer side a thick tin coating or is otherwise plated so as to prevent the formation of any poisonous substances, such as copper compounds by the gases or chemicals coming into contact with the copper cylinder.

A thermo-element *i* is introduced through the cap and connected with a variable resistance *e* for controlling the temperature of the heating element *d*.

The outer brass container *a* is closed by a copper lid *k* tin-plated on its inner side and held in position by a plurality, for example twelve, wing nuts *l* and preferably provided with an asbestos packing.

The lower end of a tube *u* having an external screw thread *v* on its upper end is inserted in a central aperture in the lid *k* and fits tightly therein. The cap *e* is then screwed onto the upper end and as the cylinder *g* is rigidly screwed in the cap *e* at its upper end it is hermetically closed at its upper end.

A draining screw *m* is provided in the bottom of the container *a* for draining off the water from condensation.

The gases are discharged through a tube *n* fixed on the lid *k* and carrying an inwardly projecting four-way nipple *o*. A cleaning plug *p* is fitted in the upper end of the tube *n*. A T-union *q* is mounted on the tube *n* and carries a cock *r*

through which the gases can be drawn off. The T-union *q* has a branch tube *s* which serves for discharging the water from condensation. A hose tap *t* is provided on the end of the tube *s* and is normally closed and opened only for the purpose of draining off the water from condensation.

The gasification is effected in the following manner:—The mixture of chemicals to be gasified is charged into the glass cylinder *c*, whereupon the heating element *g*, *d*, *e* is screwed in. The source of electric current is then connected with the plugs *f*. The cylinder *g* surrounding the heating element is heated thereby and transmits its heat to the chemicals causing them to give off gases. The thermo-element *i* is then connected with an indicating instrument, such as a pyrometer, by means of which the temperature of the heating wire can be controlled and regulated with the aid of the variable resistance.

Various experiments have shown that, by varying the chemicals of the mixture and the gas mixtures generated thereby, diseases of different kinds can be treated. This novel manner of employment of medicaments may be termed "gas therapy" or "mixed gas therapy."

I claim:

1. A vaporizer comprising in combination a brass container tin plated on its inner side, a second brass container tin plated on its inner and outer sides inserted in said first mentioned brass container, a cylinder made of refractory glass open at the top to communicate with said first mentioned container inserted in said second container and adapted to receive a mixture of chemicals, a copper cylinder in said glass cylinder and projecting above the upper end of said first mentioned container, a lid securely fixed on the upper end of said first mentioned container and having a central aperture surrounding the upper end of said copper cylinder and a lat-

eral aperture, a tube fitting tightly in said central aperture forming a tight closure between said lid and said copper cylinder, said tube having an external screw thread at its upper end, a cap fixed on the upper end of said copper cylinder and having an internal screw thread adapted to engage the screw thread on said tube to form a tight closure between said copper cylinder and said lid, a heating element fixed in said cap and extending into said copper cylinder to heat and vaporize the chemicals in said glass cylinder, discharging means fitted in the lateral aperture in said lid and adapted to conduct the vapors from said first mentioned container, and a branch tube leading from said means adapted to draw off the condensed water from the vapors passing through said means.

2. A vaporizer as specified in claim 1, comprising in combination with the cap, said cap having a central aperture in its lid, a thermo-element inserted in said aperture.

3. A vaporizer as specified in claim 1 comprising in combination with the glass cylinder and copper cylinder, a copper disc fixed on the bottom end of said cylinder adapted to uniformly distribute the heat and maintain the distance between said copper cylinder and said glass cylinder.

4. In a vaporizer as specified in claim 1 the discharging means, comprising in combination a vertical pipe fitting in the lateral aperture of the lid, a cleaning plug fitted in the upper end of said tube, a T-union, one arm of said union connected laterally with said vertical pipe and a second arm with the drain tube for the condensed water, a cock on the third arm of said union adapted to regulate the vapor flow from said union, and a hose tap on the end of said branch tube adapted to regulate the discharging of the condensed water.

WILHELM SCHMIDT.
